DOOR LATCH

Harold Walter Falk, Minneapolis, Minn., assignor
to Wright Products, Inc., St. Paul Park, Minn.,
a corporation of Minnesota

Application February 14, 1949, Serial No. 76,230

12 Claims. (Cl. 292—165)

1

My invention relates to an improvement in door latch and deals particularly with a structure which may be easily and economically mounted on a door.

Door latches of the usual type are somewhat difficult to attach to wooden doors in that most such locks include an operating mechanism which must fit within a cavity cut into the edge of the door.

A feature of the present invention lies in the fact that the lock may be mounted in a door by merely securing the structure in two intersecting holes, one of which is bored into the door edge and the other of which extends through the door between opposite surfaces thereof.

A feature of the present invention lies in the simplicity of construction and in the ease of assembly of the various parts. My door lock is constructed so that the parts thereof may be manually formed by punch press operations and thus may be formed in substantial volume at low cost.

A feature of the present invention lies in the provision of a door which includes a simple novel type of locking mechanism. By merely moving one handle of the door latch in an axial direction the lock may be engaged or disengaged. Thus the door may be locked by pressure against the door knob as the door is closed and may be unlocked by pulling upon the door knob before the door is opened, thus eliminating the requirement of an extra operation to lock or unlock the door.

A feature of the present invention lies in the provision of an eccentric door latch handle of streamlined design which presents an attractive appearance and which provides increased leverage for operating the door with a minimum of ease.

An added feature of the present invention lies in the fact that my lock is immediately applicable to doors of various types regardless of the edge thereof which is hinged. Some doors are hinged along one edge, while other doors are hinged along the opposite edge. My lock is immediately adaptable for either style of door regardless of the hinge location. At the same time the lock may be maintained on either side of the door desired so that the door may be locked from the inside or from the outside.

A feature of the present invention lies in the provision of a door latch which may be used on interior doors such as the doors of bathrooms and the like and which may be provided with means whereby the door may be opened from the opposite side in an emergency. My lock is ordi-

2

narily operated by an axial movement of the handle on its pivotal support on one side only of the door. The axial movement of the handle is transmitted through a handle shank extending to the opposite side of the door and enclosed within the handle on the opposite side of the door. An aperture may be provided in a suitable location on the opposite side of the door so that an instrument may be inserted for moving the handle axis longitudinally, thereby providing a means of unlocking the door in an emergency.

A feature of the present invention lies in the fact that the shank which connects opposite handles on opposite sides of the door is supported by a flange or rosette fastened to the face of the door. This flange or rosette includes a hub which acts as the pivotal support for the shank and facilitates the operation thereof.

A feature of the present invention lies in the provision of a novel means of holding the two handles of the door assembled. In most door latch constructions the handles are removably connected to the handle shank by set screws or other means to permit the desired variation in door thicknesses. In the present construction the flanges or rosettes which overlie opposite door surfaces are connected by suitable clamping bolts and these bolts hold the handles on the door. As a result a pull upon either door handle is resisted by the bolts connecting the flanges on opposite sides of the door.

These and other objects and novel features of my invention will be more clearly and fully set forth in the following specification and claims.

35 In the drawings forming a part of my specification:

Figure 1 is a cross-sectional view through a door at the location of my door latch showing the arrangement of the parts of the latch relative to

40 the door.

Figure 2 is a side elevational view of one side of the door showing the manner in which the latch is connected thereto.

Figure 3 is a sectional view through the door latch showing the internal arrangement of the parts thereof.

Figure 4 is a sectional view through the door latch removed from the door, the position of the section being indicated by the line 4—4 of

50 Figure 3.

Figure 5 is a side elevational view of the door latch mechanism housing with the door handles and handle shank removed.

Figure 6 is an end elevation view of the door

latch partly in section showing the movement of one of the handles to lock the door.

Figure 7 is a sectional view through the door latch looking toward one of the surface flanges or rosettes, the position of the section being indicated by the line 1—7 of Figure 3.

Figure 8 is a sectional view through a portion of the latch showing the latch in unlocked position.

Figure 9 is an end elevation view of the covering plate for the latch bolt.

Figure 10 is a sectional view through the handle shank showing the construction thereof.

Figure 11 is a perspective view of a portion of the latch operating mechanism.

Figure 12 is a sectional view through the latch looking at the opposite flange or rosette from that illustrated in Figure 7 of the drawings.

Figure 13 is a view of a detail portion of the supporting hub mechanism for supporting the latch shank.

Figure 14 is an end elevation view showing one detail of the latch.

The door latch A is used in conjunction with a door B of any suitable type or construction. The door B is preferably formed of wood or similar material and the mechanism for operating the door is mounted in two apertures 10 and 11. The aperture 10 extends into the edge of the door and extends substantially normally thereto toward the hinged edge of the door. The aperture 11 intersects the axis of the aperture A and extends from one surface 12 of the door B to the opposite surface 13 thereof.

The latch actuating mechanism is best illustrated in Figures 1, 3, 4, and 5 of the drawings. As shown in these figures the latch is enclosed by a casing indicated in general by the numeral 14 and which includes a pair of casing sides 15 and 16 which are preferably riveted together in the manner which will be described in detail.

Each of the casing sections 15 and 16 includes a hollow semi-cylindrical sleeve portion 17 which is pressed together at one end as indicated at 19 to form substantially parallel casing sides 20 and 21 at the inner ends of the casing sections. The flattened portions 19 are longer along the lower half of the casing than along the upper half thereof to better accommodate the working parts of the structure.

The casing also includes an anchoring plate 22 which is generally rectangular in outer form and which is provided with a central aperture through which the end of the sleeve-like casing portions 17 extend. The extremity of the sleeve 17 is provided with spaced fingers 23 which are bent outwardly from the body of the sleeve to overlie portions of the plate 22. However, the plate 22 is provided with a pair of opposed inwardly extending fingers 24 which engage against the end of the sleeve 17 to hold the sleeve from axial movement with respect to the plate 22. Thus the sleeve 17 is held from axial movement in one direction by the ears 23 and held from axial movement in the opposite direction by the ears 24. The plate 22 is provided with a pair of spaced apertures 25 therethrough for accommodation of screws 26 for holding the mechanism housing in place upon the door as will be later described. The plate 22 is also provided with a peripheral flange 27 which is of a thickness at least equal to the thickness of the ears 23 so that the overlying escutcheon plate may lie flush thereagainst.

The two housing parts 15 and 16 are held together by engagement of the sleeve end 17 75

through the aperture in the anchor plate 22 and also by a pivot pin 29 which extends through the flat parallel sides 20 and 21 thereof near the lower edge of the housing intermediate the ends thereof.

5 This pivot pin is provided with small diameter ends which extend through the housing portions 20 and 21 and these ends are riveted over to form a connection between the housing parts. A bell crank lever 30 preferably formed of two laminations for simplification in construction is pivotally supported upon the pivot 29 intermediate the housing sides 20 and 21. This bell crank lever 30 fits snugly between the sides so as to pivot freely within the housing without excessive axial movement.

10 A disc 31 having a notched upper edge forms a partition wall intermediate the ends of the sleeve portions 17 and ears 32 on opposite sides of the disc 31 extend through cooperable apertures in the housing portions 15 and 16 to properly locate the disc. The ends of the ears 32 may be riveted over or slit slightly to further assist in anchoring the housing portions together. The disc 31 engages one arm 33 of the bell crank lever 30 to limit pivotal movement of this bell crank lever in a counter-clockwise direction in the position illustrated in Figure 4 of the drawings.

15 The latch bolt 34 includes a cylindrical body 35 having a flattened end surface 36 formed by cutting away the cylindrical body along a chord and this bolt is also provided with an inclined cam surface 37 opposite the flattened surface 36. The inner end of the latch bolt 34 is reduced in diameter as illustrated at 39 and this reduced diameter portion is provided with a peripheral groove 40.

20 A latch bolt operating arm 41 is supported within the cylindrical sleeve portion 17 and moves axially with respect thereto. The arm 41 is best illustrated in Figures 1 and 11 of the drawings and includes an arcuate body 42 extending longitudinally of the sleeve portions 17 and substantially concentric therewith. This body 42 is provided with an inturned end flange 43 which is designed to engage in the groove 40 of the latch bolt 34. It will be noted that because of this construction the latch bolt 34 is free to rotate within the housing 14 about its axis and may be moved longitudinally in any rotative position thereof by the arm 41.

25 As indicated in Figures 1, 4, and 11 of the drawings, the arm 41 is provided with a rectangular aperture 44 therein intermediate its ends, the aperture 44 terminating at one end in an upturned shoulder 45. This aperture 44 is designed to accommodate the lever arm 33 of the bell crank lever 30 and engagement of the bell crank lever 30 in the aperture 44 permits longitudinal movement of the arm 41 and consequently of the bolt 34. The latch bolt 35 is provided with an axial recess 46 in its inner end to accommodate one end of a spring 47. The other end of the spring 47 bears against the disc 31 and is held in proper relation thereto by an indentation 49 at the center of the disc 31.

30 A crank arm 50 preferably formed of two laminations for ease in manufacture is mounted between the parallel ends 20 and 21 of the housing 14. An arcuate spacing plate 51 is provided between the flat parallel sides 20 and 21 and is held in place by laterally extending ears 53 which extend through suitable apertures in the plate portions 20 and 21. The center of arcuation of the spacing plate 51 coincides with the axis of the crank arm 50 and the adjacent end 54 of

the crank arm 50 is rounded to fit freely within the plate 51. The crank arm 50 is provided with a projecting end 55 which engages against the lever arm 56 of the bell crank lever 39. Thus the crank arm 50 is usually held from any extensive longitudinal movement between the housing parts so that the handle shank may be extended therethrough in applying the latch to the door.

The handle shank 56 in general comprises an elongated rectangular bar which is fixed relative to one handle 57. A sleeve 59 encircles the shank 56 at one end thereof. This sleeve 59 is pressed inwardly on four right angularly arranged sides as indicated at 60 so as to fit snugly about the shank 56. A pin 61 extends through the inwardly pressed sleeve portions 60 and through the shank 56 to hold these parts assembled together and to prevent any axial relative movement or relative rotative movement.

The sleeve 59 is provided with a peripheral ring or bulge 62 at a point spaced from its outer end. A collar 63 is mounted upon the sleeve 59 outwardly of the bulge 62 and extends over the bulge and inwardly thereof in spaced relation to the sleeve. The purpose of this arrangement will be later described in detail. The handle 57 is formed of an inner wall portion 64 of oval or tear drop shape and is connected by a peripheral shoulder 65 to an outwardly flaring wall 66. A suggested handle shape of the foregoing configuration is depicted in Figure 2. The outer handle portion 67 is shaped similarly to the inner wall portion and includes a peripheral flange 69 which is pressed over the wall 66 against the shoulder 65, thus forming a substantially smooth rounded handle of eccentric shape. A reinforcing plate 70 lies inwardly of the inner plate 64 within the shoulder 65 and is apertured to fit snugly about the sleeve 59. The end of the sleeve is riveted over or peened over as indicated at 71 so as to clamp the collar 63, the inner handle portion 64 and the reinforcing plate 70 between this end flange and the peripheral rim or bead 62.

In order to insure the rotation of the handle in unison with the sleeve 59 the aperture in the reinforcing plate 70 is rectangular in shape and the outer end of the sleeve 59 is deformed to fit into this rectangular opening thereby preventing rotation between the sleeve and the plate 70. As the plate 70 fits snugly within the shoulder 65 of the inner handle portion 64 rotation of the handle in unison with the sleeve is insured.

In order to properly support the sleeve 59 I provide a flange or rosette 72 which is provided with a rolled edge 73 acting to secure the rosette or flange 72 to a disc 74. The disc 74 is provided with a rectangular aperture 75 therethrough. The rosette 72 is also securely attached to a cylindrical hub or sleeve 76 which encircles the sleeve 59 and acts as a bearing therefor. The sleeve or hub 76 is of proper internal diameter to permit the sleeve 59 to rotate within the same or to move longitudinally thereof.

A rectangular locking plate 77 is mounted upon the shank 56 between the inner end of the sleeve 59 and a pin or collar 78. The locking plate 77 is thus held from longitudinal movement relative to the shank 56. The plate 77 is of proper outside dimensions to fit snugly within the aperture 75 of the disc 74 in one axial position of the shank 56. By exerting an outward longitudinal pull on the handle 57 the plate 77 may be moved outwardly out of alignment with the disc 75

74. When the plate 77 and disc 74 are in alignment the shank 56 can not be rotated, thus acting as a lock. However, when the handle 57 is pulled outwardly so as to move the plate 77 out of engagement with the disc 74, the shank 56 may be rotated freely by either of the handles.

It will be noted that the outward movement of the shank 56 relative to the rosette or flange 72 is limited by engagement of the plate 77 with a washer 80 encircling the sleeve 59 by slidable movement thereupon. The washer 80 is interposed between the fixed hub 76 and the plate 77 so as to limit outward movement of the shank by the handle 57. The handle 51 is mounted upon the other end of the shank 56. The handle 51 is in general similar in construction to the handle 57 and includes an inner portion 82 and an outer portion 83 which are rolled peripherally together. The inner handle portion 82 is provided with a peripheral shoulder 84 which connects the body of the inner portion to the encircling wall 85. The outer handle portion 83 is provided with a peripheral wall 86 which is rolled about the wall 85 in such a way as to hold the two handle portions from separation and to present a substantially smooth outer surface.

A sleeve 87 encircles the shank 56 near the free end thereof. This sleeve 87 is pressed inwardly along four right angularly arranged parts of the sleeve so as to produce a rectangular cross section sleeve portion at 89. The cylindrical outer portion 90 of the sleeve 87 is provided with an outwardly projecting bead rim 91 against which the handle 51 is clamped. A collar 92 is anchored outwardly of the rim 91 and is provided with a sleeve portion extending over the bead or rim 91 in spaced relation to the cylinder portion 90 of the sleeve. The inner portion 82 of the handle 51 is apertured to accommodate the end of the sleeve 87 and this inner portion 82 is reinforced by a reinforcing plate 93 which fits snugly within the shoulder 84 at one end thereof. The outer end of the sleeve 87 is outwardly riveted or peened at 94 so as to clamp the collar 92, the inner handle portion 82, and the reinforcing plate 93 between the rim or shoulder 91 and the flanged end 94. The aperture 95 in the reinforcing plate 93 is preferably rectangular in shape, and the outer end of the sleeve 87 is pressed into this rectangular aperture so as to prevent relative rotation between the handle 51 and the sleeve 87.

While the shank 56 and the inwardly pressed portions 60 and 89 of the sleeves 59 and 87 respectively have been described as rectangular, it will be understood that these elements could be triangular, hexagonal, or some other shape if desired, it being the intention that the shank and sleeves must rotate in unison.

As indicated in Figure 10 of the drawings the shank 56 is provided with parallel longitudinally extending grooves 96 in opposite sides thereof. The end of the shank is notched as indicated at 97 between the grooves 96. A hole 99 is also drilled through the shank 56 to connect the grooves.

A spring 100 is provided with a loop end 101 and outwardly bowed arms 102 and 103 which lie in the grooves 96 and tend to bulge outwardly therefrom. The spring 100 is provided with in-turned opposed ends 104 engaged in the aperture 99 to hold the spring in place. As the shank 56 is inserted into the rectangular cross section portion 89 of the sleeve 87 the spring 100 compresses so as to resist relative longitudinal movement

of the shank. If desired the rectangular cross section portion 89 of the sleeve 87 may have opposed channels on two sides of the sleeve so that the handle 81 may not be inserted at right angles to its proper position.

In order to support the sleeve 87 and the adjacent end of the handle shank I provide a flange or escutcheon plate 105 having secured thereto or integral therewith, a hub 106. This hub 106 is of proper internal diameter to accommodate the cylindrical portions of the sleeve 87 and to support the same. The hub 106 extends between the collar 82 and the cylindrical portion 90 of the sleeve so as to provide an overlapping joint between these parts.

An anchor plate 107 is marginally secured to the rosette or flange 105, the marginal edge 109 of this rosette or flange being rolled about the edge of the flange 107. The flange 107 is centrally apertured to accommodate the inner cylindrical end of the sleeve 87.

The flange 105, anchor flange 107 and hub 106 are secured to the sleeve 87 in the manner best illustrated in Figures 12 and 13 of the drawings. The inner extremity 110 of the sleeve 87 is provided with two oppositely disposed slits or cuts 111 at a point spaced from the inner extremity of the sleeve. A washer 112 encircles the cylindrical portion 110 of the sleeve 87 inwardly of the anchor flange 107. The portion of the sleeve 87 inwardly of the saw cuts 111 is then bulged outwardly as indicated at 113 in Figure 12 of the drawings, thus forming sleeve portions which extend beyond the periphery of the cylindrical portion of the sleeve for holding the handle units assembled.

The anchor flange 107 is provided with integral oppositely disposed sleeves 114 parallel to the shank 56 on which the handle is supported. These sleeves 114 are designed to extend through apertures in the surface of the door above and below the aperture 11 in which the shank 56 is mounted. The sleeves 114 are internally threaded to accommodate cap screws 115. These cap screws 115 extend through aligned openings in the rosette or flange 71 and the disc 74 to hold the two handle parts clamped against opposite surfaces of the door. The screws 115 are of sufficient length to permit a variation in thickness of the doors, the sleeves 114 being of a length to extend nearly through a door of minimum thickness. Thus the two rosettes or flanges encircling the shank are clamped together by means which will not permit relative rotation and which will yet accommodate doors of varying thickness. In this way the flange 74 is held from rotation and when the rectangular aperture 75 therein embraces the rectangular plate 77, rotatable with the shank 56, the shank is positively locked from rotation.

In Figure 9 of the drawings I disclose an escutcheon plate 116 which may overlie the anchor plate 22 illustrated in Figure 14 of the drawings and be secured thereto. The escutcheon plate 116 is provided with spaced apertures 117 therethrough which are spaced similarly to the holes 25 of the plate 22. Intermediate the holes 117 I provide an aperture 119 which is circular in shape throughout most of its periphery, but which is provided with a flat side 120, parallel to a vertical edge of the plate 116. This aperture 119 is designed to accommodate the projecting end of the latch bolt 34, the flat side 36 thereof engaging against the flat side 120 of the escutcheon plate aperture 119 to hold the latch 75

bolt 34 from rotation about its axis. In mounting the door latch upon a door, an aperture 10 is drilled into the edge of the door parallel to the opposite door surfaces. At a proper distance 5 from the door edge, the aperture 11 is bored through the door between the opposite surfaces 12 and 13 thereof. Apertures are also drilled through the door parallel to the aperture 11 and above and below the aperture 11 to accommodate the sleeves 114 and the cap screws 115.

In preferred form of my construction a shallow rectangular recess is formed in the door edge about the outer end of the aperture 10 to accommodate the anchor plate 22 and the escutcheon plate 116. While this is not absolutely essential it is desirable that these plates be substantially flush with the edge of the door as illustrated in Figure 1 of the drawings.

The latch housing 14 is next inserted into the aperture 10 in such a manner that the aligned shank openings 121 and 122 in the housing side portions 20 and 21 are aligned with the aperture 11 and the anchor plate 22 and escutcheon plate 116 are in their rectangular aperture. Screws 25 or other suitable fastening means may then be inserted through the aligned openings in the anchor plate and the escutcheon plate, care being taken to position the escutcheon plate so that the flat side 120 thereof is nearest the side of the door which swings inwardly as the door is opened. This places the cam surface 34 of the latch bolt in position to be retracted by a suitable keeper as the door swings into closed position.

The shank 56, together with the rosette 72 and its hub and anchor disc, are then put into position, the shank 56 being inserted through the aligned apertures 121 and 122 of the housing 14 and through the crank arm 50 within the housing. The handle 81 is next applied to the inwardly projecting end of the shank 56, the escutcheon handles 57 and 81 being parallel when applied.

The sleeves 114 of the anchor plate 107 are inserted into their respective apertures in the door and the cap screws 115 are inserted through the apertures in the rosette 72 and disc 74 and engaged in these sleeves 114. The cap screws are then tightened until the anchor plates 74 and 107 are drawn against opposite sides of the wall. It will be noted that the cap screws 115 are accessible only from the side of the door latch which controls the locking mechanism so that the lock may not be merely disengaged from the door to gain access through the door.

When the handle has been thus assembled, it will be noted that rotation of either handle in one direction will act to rotate the bell crank 39 in a clockwise direction as viewed in Figure 4, thereby moving the arm 41 to the right as viewed in this figure. The forward end of this arm is engaged in the slot 40 of the bolt 34 and thus pivotal movement of the lever 30 acts to retract the latch bolt 34 and to disengage the same from its cover. When the turning pressure on the handle is released the spring 47 urges the latch bolt 34 outwardly and returns the bell crank 39 to its initial position. The bell crank in turn returns the crank arm 50 to normal position, thus rotating the handles in unison to starting position.

In order to lock the door and prevent the latch bolt from being retracted by the handle 81, it is only necessary to press inwardly on the handle 57, sliding this handle and the shank 56 to the left as indicated in Figure 3. This action moves

the rectangular plate 77 into its aperture 75, thereby preventing rotation of the shank by either handle. In order to release the lock, it is only necessary to pull slightly upon the handle 57 before rotating the same, thus withdrawing the plate 77 from engagement in the aperture 75.

If the lock is to be used as a bathroom lock, or the like, an opening 125 may be in the handle 81 so that a suitable tool may be inserted and engaged against the projecting end of the shank 56. By using this tool as a lever, the shank 56 may be moved to disengage the locking mechanism. This procedure may be followed in an emergency in the event a child becomes accidentally locked in a room, or in any other such emergency.

The eccentric shape of the handle is of interest in that it permits the latch bolt to be more easily operated than with a circular type handle. At the same time, the streamlined shape of the handle lends much to the attractiveness of the design. In the interest of compactness of showing and to save room on the drawing sheets, the handles 51 and 81 are shown mounted with their small radius end directed toward the adjacent edge of the door. While the position of the handles may be adjusted so that the small diameter ends thereof are directed upwardly, downwardly, or toward or away from the free edge of the door, it is generally considered more attractive in appearance to mount the handles with the small diameter end pointing away from the free edge of the door in normal position.

In accordance with the patent statutes, I have described the principles of construction and operation of my door latch and while I have endeavored to set forth the best embodiment thereof, I desire to have it understood that obvious changes may be made within the scope of the following claims without departing from the spirit of my invention.

I claim:

1. A door latch including a reciprocable latch bolt, a housing for slidably supporting said latch bolt, a shank extending transversely through said housing, latch mechanism connecting said shank and said latch bolt for reciprocating said latch bolt upon rotative movement of said shank, bearings on opposite sides of the door encircling said shank and rotatably supporting the same, flanges supporting said bearings and designed to lie against opposite surfaces of the door, and means extending through the door connecting the flanges on opposite sides thereof and resilient means carried by said shank frictionally engaging one of said bearings to retain said shank in a selected position.

2. A door latch including a reciprocable latch bolt, a housing slidably supporting said latch bolt, a handle shank extending through said housing on an axis transverse to the direction of movement of said latch bolt, latch mechanism connecting said shank to said latch bolt for reciprocating the latch bolt upon rotative movement of the shank, a sleeve encircling said shank on either side of the door and rotatable with the shank, means connecting one of said sleeves to said shank to hold this sleeve from longitudinal movement on the shank, the shank being longitudinally slideable relative to the other sleeve, bearings on either side of the door encircling said sleeves and supporting the sleeves for relative rotation, flanges connected to said bearings and

engaging opposite surfaces of the door, means holding said other sleeve from axial movement relative to one of said flanges, and means extending through the door connecting said flanges and holding the same against the door.

3. The structure described in claim 2, and including a handle secured to each of said sleeves for rotation in unison therewith.

4. The structure described in claim 2, and including a locking plate on said shank and rotatable therewith, a locking member secured to one of said flanges and held from rotation, said locking member having an aperture therein designed to accommodate said locking plate in one rotative position of said plate, and means for slidably supporting said shank for limiting axial movement to move said locking plate into or out of engagement with said locking member, means cooperable with said locking plate limiting axial movement of said shank.

10 5. The structure described in claim 2, and including a locking element on said shank and rotatable in unison therewith, an apertured cooperable locking element secured in fixed relation to one of said flanges and locked to accommodate the first mentioned locking member in one rotative position thereof, and means supporting said shank for limited axial movement, means cooperable with said locking plate limiting axial movement of said shank, said locking plate being movable into and out of said aperture to lock or unlock said shank from rotation.

6. A door latch including a reciprocable latch bolt, a housing supporting said latch bolt, a handle shank extending transversely through said housing, means connecting said shank and said latch bolt for reciprocating the latch bolt upon rotative movement of said handle shank, a sleeve encircling one end of said shank, said sleeve including a portion having a substantially cylindrical outer surface, an inwardly deformed portion on said sleeve designed to contact said shank and to hold said sleeve from rotation relative to said shank, a shoulder extending about said sleeve 35 at a point spaced from its outer end, a handle portion encircling said sleeve adjacent said shoulder, a flange on the end of said sleeve clamping said handle portion to the sleeve for rotation in unison therewith, a bearing encircling the sleeve and rotatably supporting the same, a flange secured to said bearing and designed to engage the surface of the door about said shank, and means for holding said flange from longitudinal movement relative to said sleeve.

55 7. The structure described in claim 6 in which the means for holding the flange from longitudinal movement relative to the sleeve includes a deformed end on the sleeve holding said bearing adjacent said shoulder encircling the sleeve.

60 8. A door latch including a reciprocable latch bolt, a housing supporting said latch bolt for reciprocation, a handle shank extending transversely through said housing, latch mechanism connecting said handle shank to said latch bolt for reciprocating said latch bolt upon rotative movement of said handle shank, a sleeve encircling one end of said shank, means securing said sleeve to said shank for rotation therewith and longitudinal movement therewith, a cylindrical outer surface on said sleeve, a handle secured to said sleeve for rotation in unison therewith, a bearing encircling said sleeve and rotatably supporting the same, a flange secured to said bearing and extending outwardly from the shank

to overlie a portion of the door surface, a disc secured to said flange, said disc having an aperture therein, a locking member on said shank and rotatable therewith, said locking member being supported on the shank adjacent said sleeve, means for holding said locking member from longitudinal movement on said shank, said locking member supporting said shank for limiting axial movement, said locking member being movable into or out of said aperture in said disc, and cooperable means between said disc and said locking member to hold said locking member from relative rotation when engaged in said aperture.

9. The structure described in claim 8 and including a handle secured to the other end of said shank.

10. The structure described in claim 8 and including a bearing secured to the other surface of the door supporting the other end of said shank, and a handle secured to said other end of said shank.

11. A door latch including a reciprocable latch bolt, a housing slidably supporting said latch bolt, a handle shank extending through said housing on an axis transverse to the direction of movement of said latch bolt, latch mechanism connecting said shank to said latch bolt for reciprocating the latch bolt upon rotative movement of the shank, a sleeve encircling said shank on either side of the door and rotatable with the shank, means connecting one of said sleeves to said shank to hold this sleeve from longitudinal movement on the shank, the shank being longitudinally slid able relative to the other sleeve, resilient means carried by said shank frictionally

engaging said other sleeve to thereby hold said shank in a selected longitudinal position relative to said other sleeve, bearings on either side of the door encircling said sleeves and supporting the sleeves for relative rotation, flanges connected to said bearings and engaging opposite surfaces of the door, and means extending through the door connecting said flanges and holding the same against the door.

10 12. In a door latch of the class described, a handle shank, respective means slidably supporting opposite ends of said shank, fixed means adjacent a portion of said shank, locking means carried by said shank engageable with said fixed means to prevent rotation of said shank, and a bowed spring extending axially along a section of said shank, said spring frictionally engaging the interior surface of one of the means slidably supporting a shank end to maintain selective engagement and disengagement between said locking means and said fixed means.

HAROLD WALTER FALK.
